CONTROL APPARATUS FOR LOOMS

Rudolf Rossmann, Gauting, near Munich, Germany, assignor to firm of Tefag Textil-Finanz
A. G., Zurich, Switzerland

Application May 23, 1933, Serial No. 672,389
In Germany May 23, 1932

7 Claims. (Cl. 139—336)

- This invention relates to control apparatus for looms of the kind employing shuttles of the gripping or nipper type.
- Protective devices which automatically control looms, for example by stopping the loom when a warp or weft thread breaks, have hitherto only been employed so as to be dependent for their operation on the continuity of the warp or weft threads or the normal operation of shuttles of the pirn type. Devices commonly referred to as warp, weft and shuttle protectors are furthermore so slow in operation that it has hitherto proved necessary to provide considerable time intervals in the periodically repeated cycle of operations in order to ensure reliable operation of the control or protecting devices. The intervals of rest or stoppages thus imposed result in a loss of time which tends to place an undesirable limitation on the speed of operation of the loom.
- With a view to reducing delay in operation in weaving looms it has been proposed to provide electrically operated devices depending for their operation upon the continuity of the warp or weft threads, but the problem is somewhat different in the case of looms employing shuttles of the gripping or nipper type and to which the present invention relates.

- Control apparatus according to the present invention comprises two or more control circuits for operating indicating means and/or stopping the loom, each circuit being controlled by two switches in series with each other, one a timing switch and the other an operating switch, and means for controlling the operating switch in each circuit, in accordance with the condition of a thread or the operation of a part of the loom, the timing switches in all the circuits being periodically closed at determined intervals by contact-making members spaced apart upon a common carrier member such, for example, as a rotating cylinder or disc. In this way if the operating switch in any one circuit is actuated due, for example to the thread with which it may be associated breaking or being under insufficient tension, and the associated timing switch in that circuit is at the same time in the closed position, the loom will be stopped and/or the indicating means actuated.

Preferably each circuit includes a visible signalling device, such for example as a lamp, the several indicating devices being conveniently mounted upon a common base.

The invention renders it possible to control as desired the individual protecting devices and to avoid all premature or belated action. The

invention therefore has the advantage that the time intervals between the several working steps of the loom can be reduced to a minimum, thereby avoiding undesirable limitation of the speed of operation of the loom.

Preferably the operating switch in at least one of the control circuits comprises a movable member in the form of a feeler arranged between the weft feeding point and the point at which the gripping shuttle picks up the weft, the feeler being normally engaged by the weft thread so that in the event of this breaking or the tension of the thread being insufficient the feeler member closes the operating switch.

In looms of the type to which the invention relates, that is to say the type employing gripping or nipper shuttles, the projecting end of the weft after this has been introduced into the shed is sometimes bent into the succeeding shed and care must therefore be taken that the end of the weft thread is firmly held in a clip to maintain the tension in the weft until it has been beaten up and the projecting ends bent in. When therefore the present invention is applied to such a loom the operating switch in at least one control circuit may comprise a movable member in the form of a feeler arranged between the edge or selvedge of the cloth and the point at which the weft thread is held in the clip or the point at which the thread is severed, the feeler being normally engaged by the weft thread so that in the event of this breaking or the tension in the thread being insufficient the feeler member closes the switch.

Similarly if desired the operation of the operating switch in at least one of the circuits may be dependent upon operation of the shuttle. Thus when the shuttle fails to operate in the normal manner the operating switch may be actuated so that when the associated timing switch is closed, the corresponding signal is operated and/or the loom is stopped. This arrangement is particularly applicable in the case of looms employing gripper shuttles in which the shuttle boxes are fixed since, in such cases, a shuttle which has not been perfectly fitted into the shuttle box will tend to stick between this box and the reed and thus damage one or both of these parts. It is therefore important that the protecting device associated with the shuttle should act quickly and precisely at the moment when faulty operation occurs.

If desired the operating switch in at least one circuit may comprise a member carried by the heald frame so that as the heald frame moves

the operating switch is periodically opened and closed. In this way when the heald frame ceases to operate normally the operating switch associated with the heald frame and the corresponding timing switch will both be in the closed position at the same time so that the corresponding signal will be actuated and/or the loom stopped.

A further part of looms employing gripping shuttles which is liable to cause serious trouble if not operated in the normal manner is the feeder or transfer hammer whereby the weft thread to be picked is fed to the shuttle. It is particularly desirable to ensure that the feeder or transfer hammer returns from its delivery position without delay so as to allow the succeeding feeder or transfer hammer which has, for example, to supply a thread of a different color to move into the delivery position since, otherwise, the feeder hammers are liable to foul each other and thus cause damage.

With a view to obviating the possibility of such damage the operating switch in at least one circuit may comprise, according to the invention, a member whose operation is dependent upon normal operation of the feeder or transfer hammer. Thus, when the return movement of the feeder or transfer hammer from its delivery position is delayed, the operating switch associated with the hammer and the corresponding timing switch in that circuit will both be closed at the same time so that the corresponding indicating device will be actuated and/or the loom stopped.

The presently-preferred system incorporating these and other inventive concepts is shown, quite schematically, by way of illustration, in the accompanying drawing, which is an assembly, diagrammatic view.

In the construction illustrated in the drawing, a drum or cylinder 1 which is continuously rotated in the direction of the arrow is divided into annular zones 2a, 2b, 2c, 2d, 2e, and 2f which carry projections or contact bars 3a, 3b, 3c, 3d, 3e, and 3f, these contact bars being angularly and axially spaced apart on the cylinder 1. A battery 4 supplies electric current for six circuits indicated at 5a, 5b, 5c, 5d, 5e, and 5f, these circuits respectively including signal lamps 6a, 6b, 6c, 6d, 6e, and 6f mounted on a common base 7. The circuits 5a, 5b, 5c, 5d, 5e, and 5f are controlled not only by the contact bars 3a, 3b, 3c, 3d, 3e, and 3f, hereinafter referred to as timing switches, but also by switches 36-39, 28-29-30, 21-22, 19, 24-25, and 33-34-35 which will be referred to as operating switches, the timing switch and operating switch in each circuit being arranged in series with each other. The operation of each of the operating switches is dependent upon the operation of a different part of the loom or the continuity of a thread. Thus, for example, the operating switch 19 may be dependent upon the continuity of a weft thread so that when this breaks switch 19 is closed, the operation of the switch 24-25 being, for example, dependent upon the operation of a part of the loom such as, for example, the shuttle, the operation of the switch 28-29-30 may be dependent upon the operation of the heald bar, and so on.

The spacing of the contact bars 3a, 3b, 3c, 3d, 3e, and 3f for operating the timing switches 44 is such that with the cylinder 1 rotating at a substantially constant speed the contact bars 3a, 3b, 3c, 3d, 3e, and 3f will bridge the corresponding contacts in the circuits 5a, 5b, 5c, 5d, 5e, and 5f successively at time intervals corre-

sponding to the intervals between the functions of the loom in accordance with which the several operating switches are controlled. Thus, for example, if the operating switch 19 is associated with a weft thread so that in the event of this breaking the operating switch 19 will be closed, whilst the switch 28-29-30 is associated with the heald frame, the time interval between the closing of the timing switch operated by the contact bar 3d and the closing of the timing switch 10 operated by the contact bar 3b will be approximately equal to the time interval between the point at which the weft thread associated with the switch 19 is under tension in the shed and the point at which the heald frame reaches a 15 predetermined position in its movement.

The operation of the apparatus is then as follows: When one of the timing switches, for example that associated with the circuit 5d, is bridged by the contact bar 3d on the cylinder 1 20 and if at this moment the operating switch 19 is closed due, for example, to breaking of the weft thread associated with that operating switch current will flow through the circuit 5d, whereby a solenoid 9 will be energized and operate a switch 25 40 which controls flow of electric energy which is used for stopping the loom, the lamp 6d on the signal board 7 being at the same time illuminated. The attendant can then immediately locate the 30 point at which trouble has occurred. It will therefore be seen that it is not necessary to examine every vulnerable point of the loom so that considerable time is saved and the output of the loom is increased.

The operating switch 19 responds to the conditions of the weft thread 16 employed in the manufacture of a fabric 15. The weft thread 16 which is picked or shot by the nipper shuttle 14 into the shed passes between two rods 17, 18 arranged outside the edge or selvage of the cloth. Switch 45 19 which, at the same time acts as a feeler, is so arranged between the rods 17 and 18 that it is normally engaged by the picked weft thread 16. When, however, the weft thread 16 breaks or when its tension within the shed is less than that desired, the feeler 19 will drop and thus close the contacts of the operating switch. If the feeler 19 constitutes, for example, the movable contact of a switch, and when the feeler 19 and the contact bar 3d simultaneously close the contacts of 50 the operating and timing switches respectively, the solenoid 9 will be energized to stop the loom and the corresponding signal lamp 6d will be illuminated.

Switch 21-22 constitutes an arrangement particularly suitable for use in looms employing nipper shuttles in which it has been proposed to bend the ends of the weft threads, where these are severed, into the next shed for the purpose 60 of producing a selvage, this bending-in being effected by holding the two ends of the weft thread in clips which maintain the cut-off weft under tension prior to bending-in of the ends of the weft thread by suitable devices. In the event of the weft thread 16 breaking or its tension being insufficiently maintained by the clip 20, a feeler 21 which rests on the weft thread 16 will come into contact with a contact 22 of the switch. 65 If the closing of the contact 22 coincides with the closing of the corresponding contacts of the timing switch operated by the contact bar 3c, the associated circuit 5c will be closed so that the solenoid 9 will be operated to stop the loom, the 70 75

corresponding signal lamp 6c being at the same time illuminated.

Switch 24—25 operates in accordance with the operation of the shuttle. If the shuttle 14 is not driven fully into the shuttle box 23, a contact 24 will remain closed by a spring contact 25 operated by a plunger 26. If the contacts 24 and 25 are closed and when the associated contact bar 3e on the cylinder 1 closes the contacts of the timing switch in the circuit 5e, the solenoid 9 will be operated to stop the loom and the corresponding signal lamp 6c illuminated. During normal operation of the shuttle 14, that is to say, when this fully enters the shuttle box 23, the plunger 26 will force the contact 25 clear of the contact 24 during operation of the corresponding contacts of the timing switch so that the solenoid 9 will not be energized.

The heald frame 27 in moving up and down temporarily bridges, by means of a bar 28, fixed contacts 29 and 30 forming, for example, the contacts of the operating switch 28—29—30. When heald frame 27 is correctly operated, the contacts 29 and 30 are opened at the point of the reversal of the frame, that is to say, when the corresponding contacts of the associated timing switch operated by the contact bar 3b are closed. If, however, normal operation of heald frame 27 does not take place, the contacts 28, 30 will not be broken or will have been rebridged when the corresponding contacts of the associated timing switch operated by the cylinder 1 are closed by the contact bar 3b. As a result, the solenoid 9 will be operated to stop the loom and the corresponding lamp signal 6b illuminated.

Switch 33—34—35 is dependent upon correct operation of the feeder or transfer hammer which supplies thread to the gripping or nipper shuttle. When the hammer 31 enters the shuttle box 32, it moves the pin 33 so as to close two contacts 34, 35 forming the contacts of the switch. The hammer 31, however, must leave the position shown without delay after supplying the thread to the shuttle. If the hammer does not leave in time, the contacts 34, 35 will be bridged at the moment when the corresponding contacts of the associated timing switch operated by the contact bar 3f on the cylinder 1 are closed, so that the solenoid 9 will be energized and the loom stopped, the corresponding signal lamp 6f being at the same time illuminated. If, on the other hand, the hammer 31 is operating correctly, that is to say, is leaving the shuttle box 32 without undue delay, the contacts 34, 35 will be broken when the corresponding contacts operated by the contact bar 3f are closed. In this way the possibility of several hammers fouling each other and thus becoming bent or broken is obviated.

If desired, one or more of the operating switches may be dependent for its operation on the continuity or tension of warp threads; a switch mechanism may be provided comprising stationary contact members 36 which are insulated from one another and an electrically conductive bridge member 39 which is carried by the heald 37. Thus, when a warp thread 38 breaks or its tension is insufficient, the corresponding portion 39 will fall as indicated by dotted lines and connect the electric contact bars 36 so that, if at the same moment the corresponding contacts of an associated timing switch are closed, the corresponding lamp signal will be illuminated so that the attendant can immediately locate the broken or slack warp thread.

The invention, which is of particular importance for complicated weaving machines, makes it possible not only to ensure full protection against faults occurring in the cloth manufactured and protection for the sensitive parts of the loom but, in addition, provides for rapid location and rectification of any faults by the attendant. A particular advantage of the invention is, however, that the time interval between the individual working operations during which trouble is liable to occur can be reduced as desired so that the several working operations may be arranged to take place in more rapid succession and thus increase the output of the loom. The construction above described is also advantageous in that the consumption of current in the control apparatus is small since any one of the circuits is only closed when a fault occurs. It will be understood that, instead of providing contact bars of the "brush" type on a rotatable carrier member as above described, the carrier member may be furnished with means such as, for example, cams which successively actuate members constituting the movable contacts of the timing switches.

I claim:

1. In a high speed power loom having a plurality of different operating members a unified control system comprising a source of power, a continuously operating central power distributor, and periodically operating a plurality of power connectors, a plurality of power operated signals, a power conduit connecting all said connectors with said source in parallel, and a plurality of power conduits individually connecting said connectors and said signals, detectors associated with said operating members and being individually responsive to the operating conditions of said different members, power-flow control means adapted to be operated by said detectors, a plurality of power conduits individually and operatively connecting said power-flow control means with said signals, and an actuating means for stopping the operation of the loom, said actuating means being operatively connected with all of said power-flow control means and being power actuated upon simultaneous operation of said connectors and power-flow control means.

2. A unified control apparatus for high speed looms, comprising at least two electric circuits, electrically operated indicating means and electrically operated loom stopping means serially arranged within each of said circuits, timing-switch means and operating-switch means also serially arranged within each of said circuits, individual detectors adapted to individually operate said operating-switch means, each of said detectors being adapted to be responsive to the operating condition of a different part of the loom, each of said timing-switch means consisting of at least one stationary and one moving part, said moving part being adapted to periodically operate said switch means, all of said moving parts being rigidly connected to a continuously moving common carrier, whereby the speed of movement of all moving parts is maintained alike.

3. A unified control apparatus for high speed looms having a heald frame, said control apparatus comprising at least two electric circuits, electrically operated indicating means and electrically operated loom stopping means serially arranged within each of said circuits, electric current switch means and circuit opening and closing means also serially arranged within said circuits, individual detectors adapted to individually

- operate said circuit opening and closing means, each of said detectors being adapted to be responsive to the operating condition of a different part of the loom, each of said electric current switch means consisting of at least one stationary and one moving part, said moving part being adapted to periodically operate said electric current switch means, all said moving parts being rigidly connected to a common continuously moving carrier, whereby the speed of movement of all moving parts is maintained alike, at least one of said circuit opening and closing means comprising a member adapted to be actuated by the heald frame.
4. A unified control apparatus for high speed looms having a shuttle transfer hammer, said control apparatus comprising at least two electric circuits, electrically operated indicating means and electrically operated loom stopping means serially arranged within each of said circuits, electric current switch means and circuit opening and closing means also serially arranged within said circuits, individual detectors adapted to individually operate said circuit opening and closing means, each of said detectors being adapted to be responsive to the operating condition of a different part of the loom, each of said electric current switch means consisting of at least one stationary and one moving part, said moving part being adapted to periodically operate said electric current switch means, all said moving parts being rigidly connected to a continuously moving common carrier, whereby the speed of movement of all moving parts is maintained alike, at least one of said circuit opening and closing means comprising a movable contact member connected to and adapted to be actuated by said transfer hammer.
5. A unified control apparatus for high speed looms having a weft thread feeder, said control apparatus comprising at least two electric circuits, electrically operated indicating means and electrically operated loom-stopping means serially arranged within each of said circuits, electric current switch means and circuit breaking and connecting means also serially arranged within said circuits, individual detectors adapted to individually operate said circuit breaking and connecting means, each of said detectors being adapted to be responsive to the operating condition of a different part of the loom, each of said electric current switch means consisting of at least one stationary and one moving part, said moving part being adapted to periodically operate

said switch means, all said moving parts being rigidly connected to a continuously moving common carrier, whereby the speed of movement of all moving parts is maintained alike, at least one of said circuit breaking and connecting means comprising a movable contact member and adapted to be actuated by said weft thread feeder.

6. In a high speed power loom having a plurality of different operating members, a unified control system comprising a source of electric power, a plurality of control conduits connected with said source, a periodically operated switch in each of said conduits, each switch comprising a stationary and a movable part and being adapted to individually, periodically, and directly connect and disconnect said control conduits with and from said source of electric power, all said movable parts being connected with a common continuously rotating carrier, an electrically operated signal means within each of said control conduits, a circuit breaking and connecting means in each of said control conduits, each of said circuit breaking and connecting means being responsive to the operating condition of a different one of said operating members, an operating conduit interconnecting said control conduits and connected to said source of electric power, and electrically driven operating means in said operating conduit, said operating means being actuated upon closing of one of said periodically operated switches at times when one of said circuit breaking and connecting means is in connecting condition, one of said operating members being constituted by a warp thread, one by a shuttle, one by a heald frame, one by a transfer hammer, and one by a heald.

7. A unified control apparatus for high speed looms comprising a plurality of electric lines arranged in parallel, a plurality of different detectors, line breaking and connecting means connected to and adapted to be operated by each of said detectors, and a periodically-operated, momentarily acting electric current switch serially arranged in each of said lines, an electric conduit interconnecting and making up a circuit together with said lines arranged in parallel, loom-stopping means, and a source of electricity serially arranged in said conduit, whereby switching on of current flow is effected only by said current switches when said line breaking and connecting means are in line-connecting condition, and sparking is prevented at said line-breaking and -connecting means.

RUDOLF ROSSMANN.
